UNITED STATES PATENT OFFICE.

CHARLES H. LITTLE, OF PIQUA, OHIO.

UNDERGARMENT.

No. 892,277.

Specification of Letters Patent. Patented June 30, 1908.

Application filed June 12, 1907. Serial No. 378,643.

To all whom it may concern:

Be it known that I, CHARLES H. LITTLE, a citizen of the United States, residing at Piqua, in the county of Miami and State of Ohio, have invented certain new and useful Improvements in Undergarments, of which the following is a specification.

This invention relates to nether garments of the combination type generally designated 10 as union suits, in which the waist and leg portions are formed in one piece.

The purpose of the invention is to combine with the garment a seat section or reinforcement which will obviate rolling or wrinkling 15 of the seat portion of the garment when the wearer is either standing or sitting and which will avoid necessity for adjustment of the seat portion of the garment when sitting, stooping, squatting or assuming an upright 20 position or changing from one pose to another so as to secure ease and comfort and obviate binding; to prevent strain upon the buttock or inside of the leg and thereby avoid friction, galling and other objection- 25 able features resulting from rubbing, chafing or centralizing of the strain upon a particular point or line.

For a full description of the invention and the merits thereof and also to acquire a 30 knowledge of the details of construction of the means for effecting the result, reference is to be had to the following description and accompanying drawings.

While the invention may be adapted to 35 different forms and conditions by changes in the structure and minor details without departing from the spirit or essential features thereof, still the preferred embodiment is shown in the accompanying drawings, in 40 which:

Figure 1 is a rear view of a combination nether garment embodying the invention. Fig. 2 is a front view thereof. Fig. 3 is a 45 view of the inner side of the rear portion of the garment showing more clearly the position of the seat section or reinforcement.

Corresponding and like parts are referred to in the following description and indicated in all the views of the drawings by the same 50 reference characters.

The garment may be of any pattern, size or material, and is of the variety designated as combination or union suit since the waist and leg portions are of integral formation. 55 The garment, as shown most clearly in Fig. 2, opens from the neck to the crotch, said open-

ing extending a short distance in the rear to admit of spreading of the legs and buttocks. The edge portions bordering upon the opening are adapted to overlap a short distance 60 and to be secured by suitable fastening means. The garment is most generally knit so as to conform to the figure and avoid fullness and the formation of welts.

The present invention relates to a seat section or reinforcement 1 which is of the form substantially as shown in Fig. 3, being contracted at its upper end and widened and bifurcated at its lower end to conform approximately to the seat of the garment to 70 which it is attached, preferably upon the inner side. The seat section is formed preferably of goods similar to that entering into the formation of the garment and by being placed upon the inner side of the seat portion 75 of the garment and being stitched thereto at its upper and lower ends, not only prevents spreading of the garment at the waist but insures comfort and ease to the wearer and prevents the edge portion of the garment 80 from passing between the limbs, rolling so as to form welts, or binding upon the buttocks or rubbing and chafing when changing from one position to another, at the same time not interfering with the natural functions in 85 evacuating the bowels or micturition. The bifurcated portions of the seat section or reinforcement extend a short distance along the upper portions of the leg sections and are stitched thereto at their lower edges as indicated by the lines of stitching 4—5 and 6—7. The upper end of the seat section is stitched to the waist portion of the garment along the line 2—3. The edge portions from 2 to 4 and 3 to 7 are loose and the inner edge portions 95 from 5 to 8 and 8 to 6 are free. The general outline of the seat section and the manner of attaching the same to the nether garment are essential in order to attain the advantages of the invention in securing ease and comfort to 100 the wearer and to prevent annoyance and galling which commonly result from union nether garments as generally constructed.

Having thus described the invention, what is claimed as new is:

1. An under garment comprising leg portions and having an opening in the front extended around the crotch and upward in the rear to near the waist line, the parts bordering upon the opening being overlapped, a 110 seat section applied to the inner side of the seat portion of the garment and having its

lower part bifurcated and the outer edges of the bifurcations rounded, thence upwardly converged, said seat section having the form substantially as shown and having its top 5 edge stitched transversely to the waist portion of the garment, and having the outer rounded edge portions of the bifurcations stitched to the leg portions of the garment, the inner edge portions of the bifurcations 10 being loose and the upper outer converged edge portions likewise being loose.

2. A combination under garment having an opening extended from the neck downward in the front, thence around the crotch 15 and upward in the rear to within a short distance of the waist, the portions bordering upon the opening being overlapped, and a seat section having the form substantially as

shown fitted to the inner side of the seat portion of the garment and having its upper 20 portion contracted and its lower portion widened and bifurcated, the outer edges of the bifurcations being rounded and thence upwardly converged and the inner edge portions of the bifurcations being straight, said 25 seat section being stitched at its upper edge transversely to the waist portion of the garment and having the outer rounded edge portions of the bifurcations stitched to the leg portions of the said garment.

In testimony whereof I affix my signature in presence of two witnesses.

CHARLES H. LITTLE. [L.S.]
